CLAIM

The ornamental design for a vehicle door storage unit as shown and described.

DESCRIPTION

FIG. 1 is a perspective view of a vehicle door storage unit, showing my new design.

FIG. 2 is a front elevational view of the vehicle door storage unit of FIG. 1, the rear elevational view being a mirror image thereof;

FIG. 3 is a right-side elevational view of the vehicle door storage unit of FIG. 1, the left-side elevational view being a mirror image thereof;

FIG. 4 is a top plan view of the vehicle door storage unit of FIG. 1; and,

FIG. 5 is a bottom plan view of the vehicle door storage unit of FIG. 1.

The evenly-spaced broken lines in the drawings are included for purpose of illustrating portions of the vehicle door storage unit that form no part of the claimed design. The dot-dash-dot broken lines in the drawings are included for the purpose of defining the boundary of the claim, it being understood that the region between the dot-dash-dot broken lines and the dot-dash-dot broken lines themselves form no part of the claimed design.
